UNITED STATES PATENT OFFICE

IRVIN W. HUMPHREY, OF WHARTON, NEW JERSEY, ASSIGNOR TO HERCULES POWDER COMPANY, OF WILMINGTON, DELAWARE, A CORPORATION OF DELAWARE

PROCESS OF PRODUCING A TURPENTINE SUBSTITUTE FROM PINE OIL

No Drawing.

Application filed July 20, 1926. Serial No. 123,814.

In the process for the extraction of rosin from resinous wood, there are also recovered substantial quantities of pine oil and turpentine. Since turpentine is usually more valuable than pine oil, and since other operations carried on by the producer may require the use of larger quantities of turpentine, for solvent or other purposes, than is produced in the wood extracting process, there 5 may be no use, or but a limited use, for pine oil; or, due to temporary market conditions, there may be little demand for pine oil and a big demand for turpentine. I have discovered that pine oil may be converted into a 10 substance that may be used, for most or all purposes, as a substitute for turpentine, and that has, in general, solvent properties superior to those of turpentine, although inferior to those of pine oil. 15 I have also discovered that my process may be so carried out as to produce a limited, but substantial, amount of other products, particularly borneol, which may have, as borneol has, a higher value per unit weight 20 than either pine oil, or the turpentine substance, or turpentine.

My process comprises the dehydration of pine oil by means of clay or any argillaceous earth, preferably fuller's earth, but I do 25 not intend to confine myself to the use of any specific variety of argillaceous earth, except where specifically claimed.

Fuller's earth appears to dehydrate by virtue of surface catalysis. It is possible to 30 also effect dehydration by means of other substances which appear to function in a similar manner, namely, activated carbon and silicious materials such as kieselguhr.

The preferred method of executing my 35 process involves the addition of fuller's earth to the pine oil in the proportion of about two per cent, although the proportion added may vary from 0.5 to 25 per cent, depending upon operating conditions and the character of the 40 product which is desired. The hydrocarbons are slowly distilled off, preferably with the use of steam, through a fractionating column substantially as rapidly as they are formed.

The chief constituent of pine oil is alpha- 45 terpineol, but considerable amounts of other

oxygenated bodies, as well as a small proportion of terpene hydrocarbons, are also present. The distillate comprises mainly terpene hydrocarbons that are isomeric with pinene. The main reaction may be represented thus: 55

Dipentene is the most important hydrocarbon that is formed, but other terpene hydrocarbons, such as terpinene and limonene, are 60 present. In addition, smaller amounts of paraffin and aromatic hydrocarbons may be formed in certain cases.

The specific gravity of the distillate at 15° C. is within the range .855 to .89, with between sixty-five to ninety-five per cent. distilling off below 185° C. 65

The distillate has properties which make it more similar to turpentine than to pine oil.

The high boiling point residue amounts 70 to from ten to thirty-five per cent of the original volume of pine oil. It has a specific gravity, at a temperature of 15° C., within the approximate range, .94 to .99. It consists essentially of various constituents of 75

pine oil that have not been converted into the product above described, which I designate solvenol. The residue is adapted for use as an ingredient of disinfectants. Some 80 of the constituents of the residue are more valuable than either pine oil, solvenol or turpentine. One of these more valuable constituents is borneol. Of these valuable constituents borneol, at least, is not present in substantial amounts unless a mild dehydrating agent, such as fuller's earth, or a halogen, such as iodin, is employed. It is not my intention, however, to include a halogen

as an equivalent for fuller's earth, as the use 85 of a halogen forms part of the subject-matter of another application filed by me of even date herewith; and, moreover, fuller's earth has certain advantages over a halogen, such as cheapness and the production of a 90 crude distillate of lower acidity, which makes its use of distinct commercial advantage.

The borneol may be partially recovered 95 from the residue by cooling with crystallization. Additional borneol may be recovered 100

by fractionation of the residue, followed by cooling of the fractions.

15 The density, boiling range and percentage of the distillate may vary somewhat according to conditions. It may be desirable to redistill or to make several cuts in the distillate. It is usually preferred to give the distillate an alkali wash.

18 The amount of fuller's earth used should be limited and the primary product should be removed from the fuller's earth as soon as possible, in order to avoid subsequent polymerization. It is preferable to perform the reaction at 125-225° C. (say 170° C.) by 25 distilling with steam. It is probable that the formation of a limited quantity of polymerized pine oil cannot be entirely avoided.

26 It will now be observed that by virtue of my invention not only is an efficient and economical method for the production of a turpentine substitute provided, but in addition borneol is produced in substantial proportion.

25 It will be understood that in claiming fuller's earth I mean to include, as equivalents, the substitutes herein specifically mentioned, such as other argillaceous earths, siliceous earths, as kieselguhr, and activated carbon.

32 Having now fully described my invention, what I claim and desire to protect by Letters Patent is:

35 1. The process of producing a turpentine substitute from pine oil which comprises adding fuller's earth to the pine oil and distilling.

40 2. The process of producing a turpentine substitute from pine oil which comprises adding fuller's earth to the pine oil and distilling with steam at a temperature between 125° C. and 225° C.

45 3. The process of securing a turpentine substitute and borneol from pine oil which comprises adding fuller's earth to the pine oil, distilling off hydrocarbons comprising the turpentine substitute, and separating the borneol from the residue.

50 4. The process of producing a turpentine substitute from pine oil which comprises contacting pine oil at a temperature between 125° C. and 225° C. with fuller's earth.

55 5. The process of treating pine oil which includes subjecting the pine oil to treatment with fuller's earth, while distilling at a temperature below about 225° C. and separating borneol from the residue after distillation.

60 6. The step in the process of producing a turpentine substitute from pine oil which comprises subjecting pine oil to treatment with fuller's earth in the presence of heat.

65 In testimony of which invention, I have hereunto set my hand at Kenvil, N. J., on this 26th day of June, 1926.

IRVIN W. HUMPHREY.
